UNITED STATES PATENT OFFICE

HAMILTON NEIL WYLIE AND PERCY GEORGE CRABBE, OF COVENTRY, ENGLAND, AS-
SIGNORS TO SIR W. G. ARMSTRONG WHITWORTH AIRCRAFT LIMITED, OF COVENTRY,
ENGLAND

RIVETING MACHINE

Application filed March 3, 1931, Serial No. 519,859, and in Great Britain April 7, 1930.

This invention relates to a machine for use in fixing pierced or tubular rivets, of the kind in which the rivet is mounted on a mandrel having an enlarged end so that, 5 when the rivet is inserted in position, by thrusting upon the head of the rivet and simultaneously pulling upon the mandrel the latter's enlarged head expands and upsets the rivet. The plain stem of the mandrel projecting beyond the rivet head can then be screw-threaded to receive a nut or otherwise adapted for securing attachments; or it may be cut off short or even pushed back. Alternatively, the riveting operation 10 may be such as is described in British patent specification No. 286,471, in which the mandrel is drawn completely through the rivet.

The object of the invention is to provide a reliable machine by which the fixing of such rivets can be easily and quickly accomplished, particularly when the mandrel is to be pulled completely through, when material forces 15 are met with in distorting the mandrel head.

According to the invention, a riveting machine, for use in fixing such rivets, is operable on the rotation of an actuating member in one direction first to clamp the mandrel between two elements and then to draw the mandrel substantially axially. A preferred 20 machine comprises a number of hinged members arranged so that on rotation of the actuating lever two of the members are first drawn towards one another to clamp the mandrel therebetween, and then held in these 25 relative positions whilst being rotated as a whole to draw the mandrel substantially axially.

In the accompanying drawings illustrating the invention,

Figure 1 is a side elevation partly in section, of a complete riveting machine,

Figure 2 is a perspective view of the various parts of the linkwork forming the actual 45 mandrel-gripping and moving device, the parts being shown unassembled for clearness.

Figure 3 is a perspective view of the arrangement of Figure 2, shown in the assembled position,

Figure 4 is a vertical section of the arrangement in Figure 3,

Figures 5 and 6 are similar sections of modified arrangements, and

Figure 7 is a section of a detail.

In the constructions illustrated, the machine has vertically-arranged links and is adapted for moving the mandrel horizontally. In Figure 1 the links are carried by a stationary frame 2 provided with feet 3 or 40 with wheels to enable it to be transported. The actuating means involve a pedal 4 at one end of a primary lever 5, the other end of which is connected by a substantially vertical link 6 to the lower end of an actuating 45 lever 7 hinged at 8 upon a vertical channel frame member 9 just below the point where the mandrel 10 is disposed when the machine is being operated, such that on the depression of the pedal the actuating lever is rotated upwardly in the direction of the arrow A about its fixed centre 8.

Referring now to Figures 1-4 and Figure 7, one of the elements for use in gripping the mandrel 10 is a U-shaped or strap element 11 75 adapted to pass over the mandrel and provided with an internal block 12 shaped to grip the mandrel. The other element is a vertical flat link 13 fitting within the strap and provided with a groove 14 to engage the underside of the mandrel. These two elements are hereinafter referred to as the outer and centre members, respectively. They are connected to one another for relative movement in a vertical direction by means of a pin 15 secured 80 to the centre member near the upper end and operating in a slot 16 in the outer member. Normally these elements lie against the rear face of the vertical frame member 9 adjacent to a hole therein receiving a bush 17 through 85 which the mandrel extends during the riveting operation, the nose of the bush engaging the rivet head 18 (Figure 7). The outer member 11 is held in this position by being lightly frictionally gripped by the frame 90 until the mandrel is clamped between the outer and centre members when the grip of the frame is easily overcome. In other words the outer member 11 is a press fit in the channel frame member 9.

The centre member 13 is pivotally mounted at its lower end at 19 on a link 20, herein-after referred to as the bottom member, which is in turn pivotally mounted at its lower end at 21 on the frame. The bottom member 20 has an offset portion away from this face of the frame which is pivotally linked at 22 and 23 through a short link 24, limited for relative angular movement in one direction, to the lower end of the outer member 11. All these links are disposed within the sides of the channel frame member.

On the outer member 11 there is mounted a distance piece shown as a roller 25 disposed 15 to engage the rear face 26 of the centre member 13 and to hold the pivot pin 23 in position when there is no mandrel between the gripping members. A point on the outer member, for example, the hinge pin 27 for 20 the roller, is connected by a pair of similar short links 28 to the actuating lever 7, being pivoted to the latter at 29.

When the actuating lever 7 is rotated upwardly about its fixed centre by depressing 25 the pedal 4, the thrust is transmitted through the short links 28 to the outer member 11, this thrust urging the outer member rearwardly—to the left, Figure 4. During the initial part 30 of this movement, as the upper end of the outer member 11 is held against lateral movement by frictional engagement with the stationary frame, the lower end of the outer member is caused to turn about the upper end. As the lower end is linked by the short 35 link 24 to the bottom member 20 (the lower end and link forming a straightened toggle), the upper end of the outer member is drawn down towards the centre member 13 and thus clamps the mandrel firmly. This clamping 40 is effected during quite a small movement of the actuating lever.

On further rotation of the latter, owing to the linkage formed by the outer member 11, the bottom member 20 and the interconnecting link 24 having been collapsed as much as possible, i. e., owing to the mandrel preventing further sliding of the outer member over the centre member, the linkage mechanism as a whole rotates about the fixed centre 21 at 45 the lower end of the bottom member 20. If the distance of this centre from the mandrel is relatively great the mandrel will be drawn substantially axially by this operation, and the clamping pressure will not be relaxed. 50

When the pressure is released from the pedal and the actuating lever returned to its off position the parts re-set, the clamping elements opening to release the mandrel, which can then be withdrawn by hand.

Conveniently a strap 30 is disposed around the mechanism and secured to the frame to limit the rotation of the mechanism about the lower fixed centre. This strap or stop is provided with an adjustment (not shown) so 55 that the mandrel may be drawn into a rivet

to exactly the extent desired and then released, when it is desired to leave the mandrel in the rivet.

It will be seen that by means of the invention mandrels can be very quickly operated 70 and in a simple manner, and, furthermore, a very considerable clamping effect is applied to the mandrels, which does not decrease while a mandrel is being drawn axially. Consequently the likelihood of a mandrel 75 slipping out of the machine when the main load comes on the machine is obviated.

It will be evident that the principles of the mechanism described are not restricted to cases in which the mechanism is arranged 80 vertically. Moreover, the mechanism may be modified in various ways. For example, as shown in Figure 6, the centre and bottom members 13 and 20, respectively, may be formed integrally as a single link such as 85 31, the other members being modified accordingly. Alternatively the short link 24 connecting the outer member 11 to the bottom member 20 may be dispensed with and these two members pivoted directly to one another 90 as at 32, Figure 5.

What we claim as our invention and desire to secure by Letters Patent of the United States is:—

1. A machine for use in fixing a tubular 95 rivet by drawing a mandrel into it, comprising two elements, an actuating member, and means whereby, on rotation of said actuating member in one direction, the mandrel is first clamped between said two elements 100 and then drawn substantially axially.

2. A machine for use in fixing a tubular rivet by drawing a mandrel into it, comprising hinged members, an actuating lever, and means whereby on rotation of said actuating lever two of said members are first 105 drawn towards one another; to clamp the mandrel therebetween, and then held in these relative positions whilst being rotated as a whole to draw the mandrel substantially 110 axially.

3. A machine for use in fixing a tubular rivet by drawing a mandrel into it, comprising a frame, members for gripping the mandrel, means for supporting said gripping members from said frame at one point, an actuating member pivoted on said frame, a link interconnecting said actuating member and one of said gripping members and forming 115 with said actuating member an unstraightened toggle, and means whereby when said toggle is moved in a straightening direction said gripping members are first operated in a gripping direction and then moved as a whole about said one point to draw the 120 mandrel substantially axially whilst said gripping pressure is being maintained.

4. A machine for use in fixing a tubular rivet by drawing a mandrel into it, including a stationary frame, a system of hinged 125

links pivoted at one point to the frame, two of the links being connected together adjacent their gripping ends by a slidible pivot, an actuating lever pivoted to the frame and connected to one of said two links, and means whereby movement of said actuating lever first causes said two links to be drawn together to grip the mandrel and then effects movement of the whole linkwork about its pivotal attachment to said frame to move the mandrel axially.

5. A machine for use in fixing a tubular rivet by drawing a mandrel into it, comprising a frame, an outer member in the form of a strap, a centre member, said outer and centre members being adapted for gripping the mandrel, means interconnecting said members adjacent their gripping ends for limited relative movement in a direction to grip and release the mandrel, frictional means for initially holding said outer member against rearward movement, an indirect hinged connection between said members, an indirect hinged connection between said centre member and said frame including a pivot on said frame about which said members can be rotated as a rigid entity after the mandrel has been gripped, an actuating member pivoted on said frame, and a connection between said outer member and said actuating member.

6. A machine for use in fixing a tubular rivet by drawing a mandrel into it, comprising a frame, an outer member in the form of a strap, a centre member, said outer and centre members being adapted for gripping the mandrel, a pin carried by one of said members adjacent its gripping end and engaging a slot in the other of said members to limit them for relative movement in a direction to grip and release the mandrel, frictional means for initially holding said outer member against lateral movement, a bottom member hinged on said frame, a hinged connection between said centre member and said bottom member, a hinged connection between said outer member and said bottom member, an actuating member pivoted on said frame, and a connection between said outer member and said actuating member.

7. A machine for use in fixing a tubular rivet by drawing a mandrel into it, comprising a frame, an outer member, a centre member, said members being adapted for gripping the mandrel, means interconnecting said members at their gripping ends for limited relative movement in a direction to grip and release the mandrel, a bottom member pivoted to the other end of said centre member, a link connecting the other end of said outer member to said bottom member, said link and outer member forming a partially-collapsed toggle, a hinged connection between the other end of said bottom member and said frame, an actuating member pivoted on said frame,

and a link interconnecting said outer and actuating members and forming with said actuating member a partially-collapsed toggle, such that, when said second-mentioned toggle is moved in a straightening direction, said first-mentioned toggle is first further collapsed to firmly grip the mandrel and said outer, centre and bottom members are then turned as a whole about said hinged connection between said bottom member and said frame to draw the mandrel substantially axially, while the gripping pressure increases approximately proportionately with the load on the mandrel.

8. A machine for use in fixing a tubular rivet by drawing a mandrel into it, comprising a frame, an outer member, a centre member, said members being adapted for gripping the mandrel, means interconnecting said members at their gripping ends for limited relative movement in a direction to grip and release the mandrel, a bottom member, a link connecting the other end of said outer member to said bottom member, said link and outer member forming a partially-collapsed toggle, a hinged connection between the other end of said bottom member and said frame, frictional means for holding the gripping end of said outer member against rearward movement when the machine is first actuated, an actuating member pivoted on said frame, and a link interconnecting said outer and actuating members and forming with said actuating member a partially-collapsed toggle, such that, when said second-mentioned toggle is moved in a straightening direction, said first-mentioned toggle is first further collapsed to firmly grip the mandrel and said outer, centre and bottom members are then turned as a whole about said hinged connection between said bottom member and said frame to draw the mandrel substantially axially, while the gripping pressure increases approximately proportionately with the load on the mandrel.

In testimony whereof we have signed our names to this specification.

HAMILTON NEIL WYLIE.
PERCY GEORGE CRABBE.
